UNITED STATES PATENT OFFICE.

CHARLES H. MORGAN, OF WEST CHESTER, PENNSYLVANIA.

COMBINED CANE AND UMBRELLA.

SPECIFICATION forming part of Letters Patent No. 442,491, dated December 9, 1890.

Application filed February 24, 1890. Serial No. 341,629. (No model.)

To all whom it may concern:

Be it known that I, CHARLES H. MORGAN, of West Chester, in the county of Chester and State of Pennsylvania, have invented a new 5 and Improved Combined Cane and Umbrella, of which the following is a full, clear, and exact description.

My invention is a combined cane and umbrella; and the object of my invention is to 10 provide a neat and convenient device which will operate as a cane or umbrella and which may be quickly and easily changed from one to the other.

This construction will be hereinafter fully 15 described, and specifically pointed out in the claims.

Reference is to be had to the accompanying drawings, forming a part of this specification, in which similar letters of reference indicate 20 corresponding parts in all the views.

Figure 1 is a vertical section of the device; Fig. 2, a view of the device with the umbrella-top mounted and spread upon the tube, a portion of the cover being removed to show 25 the position of the ribs, stretchers, and runner; Fig. 3, an enlarged detail view of the crown-piece and of the rod attached thereto, which limits the upward movement of the runner; and Fig. 4, an enlarged detail view of 30 the runner by which the umbrella is operated.

The tube A, which constitutes the body of the cane and the stick of the umbrella, is hollow, as shown, and may be made of any suitable material. It is closed and reduced at its 35 lower end, forming a shoulder l, and its reduced end is screw-threaded to fit the internal screw-thread of the removable nipple B. Its upper end is internally screw-threaded to receive the removable handle C, which is 40 screwed therein. Within the tube is the umbrella-top, which consists of the ribs D, suitably covered, the stretchers E, attached thereto, the crown-piece F, to which the upper ends of the ribs are attached, and the runner H, to 45 which the inner ends of the stretchers are attached. The ribs D and stretchers E are of the usual construction, may be covered with any suitable material, and need no detailed description.

50 The crown-piece F is composed of a number of links joined together at the ends, to each of which a rib D is attached, and the

diameter of the crown-piece is such that it will rest upon the shoulder l of the tube A without sliding down the body of the tube. 55 The crown-piece F is also provided with a depending rod a, which extends down the outside of the tube A when the crown-piece is in position thereon, and its lower end striking the runner H determines the upward movement of the runner upon the tube.

The runner H is composed of a number of vertical slats hinged together at the sides, so that the runner may be folded or collapsed, and thus occupy little space. The upper end 65 of the runner is provided with a series of brackets b, to which the inner ends of the stretchers E are attached. Attached to one side of the runner H is a vertical flat spring d, which extends below the lower end of the 70 runner and terminates in a curved end d', which bears against the tube A and holds the runner in position thereon, and which also serves as a thumb-piece, by which the position of the spring and runner may be regulated. The spring d is attached to the runner H by an inverted-U-shaped bracket e, which clasps the spring, and in which the spring is longitudinally or vertically movable, and the spring is prevented from being removed from 75 the bracket e by the raised arm f, each end of which is attached to the spring d. The pressure with which the spring d bears upon the tube A is regulated by moving it in the bracket e. If the spring is drawn well out, 80 the pressure of the curved portion d' upon the tube will be light, and the runner H may be easily moved thereon. If the spring is pushed inwardly, or rather upwardly, the leverage between the bracket e and curved end d' will 85 be shorter. Consequently the pressure will be greater and the runner H will be retained in position upon the tube.

Supposing the device to be in a cane form, as shown in Fig. 1, and it is desired to put it 95 in the form of a raised umbrella, the nipple B and the handle C are removed from the tube A, and the top, with the parts attached, is withdrawn from the tube. The tube is then pushed through the runner H and crown-piece F; and the crown-piece will rest upon the shoulder l. The nipple B is then screwed upon the reduced end of the tube A, holding the umbrella-top in position thereon, the han-

dle C is screwed into the open end of the tube, and the umbrella is ready for use. To change from an umbrella to a cane, the above action is reversed.

5 A circular piece of rubber or other suitable material may be placed upon the tube A between the crown-piece F and nipple B to prevent the umbrella-top from being worn.

Having thus described my invention, I 10 claim as new and desire to secure by Letters Patent—

1. A combined cane and umbrella consisting in a hollow stick A, having a detachable ferrule B at one end and a detachable handle 15 at its opposite end, the detachable umbrella-top having a link crown-piece provided with a depending rod α , a collapsible runner H, adapted to abut at its upper end against the lower end of the rod α , and a sliding spring d, 20 mounted on the outer side of the sections of the runner and curved inwardly at its lower end under the lower edge of the runner to engage the stick, substantially as set forth.

2. The combination, with the tube A, ribs D, and stretchers E, of the collapsible runner 25 H, adapted to slide upon said tube and having means, as spring d, with curved end d', bracket e on the outer side of one section of the runner, and raised arm f, crossing the bracket e at right angles, for holding it in position thereon, substantially as described.

3. In a combined cane and umbrella, the collapsible runner H, having means, as brackets b, for connecting with the umbrella-stretchers, and having means, as spring d, 35 with curved end d', bracket e on the outer side of one section of the runner, and raised arm f, crossing the bracket e at right angles, for holding it in position upon the umbrella-stick, substantially as described.

CHARLES H. MORGAN.
